UNITED STATES PATENT OFFICE

132,214

DESIGN FOR A FLUORESCENT TABLE LAMP

Carl Edward Swanson, Chicago, Ill.

Application March 13, 1942, Serial No. 106,191

Term of patent 14 years

To all whom it may concern:

Be it known that I, Carl Edward Swanson, a citizen of the United States and residing in Chicago, in the county of Cook and State of Illinois, have invented a new, original, and ornamental Design for a Fluorescent Table Lamp, of which the following is the specification, reference being had to the accompanying drawing, forming a part thereof.

On the drawing:

Fig. 1 is an elevational view of the fluorescent table lamp, showing my new design.

Fig. 2 is a top plan view thereof.

I claim:

The ornamental design for a fluorescent table lamp, substantially as shown.

CARL EDWARD SWANSON.
